FORM AND PLATEN FOR USE IN PRINTING AND EMBOSSED PRESSES

Application filed January 24, 1929, Serial No. 334,838, and in Great Britain January 24, 1928.

This invention relates to improvements in forms for holding type or matrices for use in connection with printing and embossing presses, and in platens for use in combination therewith.

The said invention provides an arrangement of bars between which the type or matrices are held and means for locking the bars together in pairs so as to hold the type between them, the means for locking together the bars being also employed for holding the type or matrices against longitudinal displacement in the bars. The bars are provided with means whereby they can be supported on frame parts which may, if desired, form part of or be attached to a platen on which the paper, cardboard or other material to be printed upon or embossed is supported while the type are subjected to pressure to make an imprint or impression thereon.

In the accompanying drawings,

Figure 1 is an end view,

Figure 2 is a plan, and

Figure 3 is a side view of a platen and forme arranged in accordance with this invention.

Figures 4 and 5 are, respectively, a face view and an edge view of a type or matrix suitable for use with the improved form, drawn to a larger scale.

Figure 6 is a face view of a group of assembled type, and

Figure 7 is an edge view of a distance piece hereinafter described.

Figures 8 and 9 are, respectively, a face view and an edge view of a further form of distance piece.

Figure 10 is an edge view, and

Figure 11 is a side view of a clip for retaining the type or matrix in position between type supporting bars.

Figures 12, 13 and 14 are, respectively, a sectional side view, a plan view, and an end view, of a modified arrangement of the improved platen and form.

As shown in Figures 1, 2 and 3, a platen 10 is provided with lateral flanges 11. A saddle bar 12 is attached to each flange 11 by screws or pins 13 passing through slots 14 in the bar 12 allowing a rising and fall-

ing movement of the bar relatively to the corresponding flange (Figure 1) but preventing relative longitudinal movement of these parts. A slide bar 15 held between the flange 11 and bar 12 is provided with pins or screws 16 passing through slots 17 in the saddle bar so that whilst a limited longitudinal movement of the slide bar relatively to the flange 11 and saddle bar 12 is permitted the slide bar and saddle bar rise and fall together. The slide bar 15 has oblique slots 18 formed therein through which the screws or pins 13 pass.

When the slide bar 15 is moved to the right from the position in which it is shown in Figure 3, the slots 18 riding on the screws or pins 13 lift this bar and also raise the saddle bar 12 through the pins or screws 16 travelling in the slots 17. The slide bars on opposite sides of the platen are connected by a handle bar 19 by which the slide bars can be moved simultaneously and thumb pieces or lugs 20 are provided on the saddle bars for conveniently holding the latter whilst the slide bars are moved, relatively thereto, more especially when the slide bars are being returned to the position in which they are shown in Figure 1.

Saddle pieces 21 are attached to the saddle bars, for example, by screws 22, or may be formed integrally with these bars, these saddle pieces preferably being formed to fit over the flanges 11 and thus assist in maintaining the bars 12, 15 attached to the flanges. The saddle pieces 21 are formed with apertures 23 in which rods or rails 24 are mounted. These rods or rails may be of circular, oval or other cross section but are preferably of rectangular cross section as shown. The rails 24 have grooves 24a formed therein which slide on the saddle pieces as the rails are inserted in the apertures 23 and prevent longitudinal displacement. The grooves 24a are of the nature of saw cuts of a width equal to the thickness of the saddle pieces 21, as shown in Figure 3, and the depth of the grooves is apparent from a consideration of Figure 1 in which the bottoms of the grooves are indicated in broken lines which also indicate the edges of the apertures 23. The

grooves in different faces of the rails can be made of different depths so that by inverting the rail the height at which it is supported above the saddle bar can be altered.

Type or matrix supporting bars 25 are suspended from the rails 24 by hooks or clips 26 preferably of tubular form threaded on the rails and slid able thereon to different positions. These hooks or clips may be retained in any positions to which they may be adjusted by frictional engagement of the clips with the rail, or set screws may be provided to clamp them in the desired positions with type or matrices held between pairs of supporting bars 25. Thus a number of lines of type or matrices may be carried by the rails 24 assembled together for use in a press.

The type or matrices 27 are provided with slots 28, Figures 4 and 5, to engage ribs 29 on the supporting bars 25, the slots being somewhat wider than the ribs, but it is evident that shoulders or ribs may be provided on the type or matrices to engage in grooves or slots provided in the bars. Although the space between the lower wall of the slot 28 and the underside of the rib cannot be seen in Figure 7, since in that figure they are concealed by the clip extension 31, the difference of size of the slot and rib will be noted upon comparison of Figure 5 with Figure 10. The type or matrices held between a pair of supporting bars are spaced apart for example, in groups forming words, and held against longitudinal displacement in the supporting bars by distance pieces which may simply rest on the supporting bars or may be clipped thereto, these distance pieces being also adapted, if desired, to hold the supporting bars properly spaced apart and locked together in pairs. Thus, a line of type or matrices can be set up between two supporting bars and a distance piece clipped to the said bars at each end of this line to prevent endwise displacement of the type whilst they simultaneously prevent separation of the bars so that a pair of the latter with type or matrices set up between them can be moved from place to place without disturbing the order, spacing or position of the type. By reason of the ribs 29 engaging in the slots 28, the supporting bars can even be inverted without the type or matrices becoming displaced. Also a number of lines of type or matrices may be kept set up in supporting bars which can be threaded on to rails or removed therefrom as may be required, and groups of lines thus set up can be held assembled on rails constituting a forme which can be mounted in the saddle pieces or detached therefrom and carried from place to place without disturbing the assembly.

An edge view of a suitable form of distance piece 30 provided with clips at each end is shown in Figures 6 and 7 comprising a body of a suitable length to be inserted be-

tween the supporting bars 25. At its ends this body is provided with thin extensions 31 which, when the distance piece is in use, rest on the bars 25, said extensions being preferably bent to conform to the shape of the flanged bars as shown. In addition each end of the distance piece can be provided with a spring clip 32 which, when in use, is pressed against the side of the bar opposite to that with which the corresponding extension 31 is in contact. These distance pieces provided with clips may also serve to hold together pairs of supporting bars 25 when the latter are removed from the rails of the form.

The distance pieces may be arranged to rest on the ribs 29 or between the ribs of adjacent bars. They may be provided with clips at both ends for engagement with the bars 25, or each distance piece may have a clip at one end only. As the separation of the bars 25 can be determined by the hooks or clips 26 clamped to the rails 24, the distance pieces can be made like the type or matrices 27, with slots to engage the ribs 29. Another suitable form of distance piece 30a is shown in Figures 8 and 9 made from a flat plate slotted at the ends with parts 30b bent oppositely outwardly. This plate may be of a resilient material, the parts 30b acting as clips gripping the ribs 29.

Short clips 32a, shown in Figures 10 and 11 may be pressed on to the ribs 29 to prevent movement of the type or matrices longitudinally on these ribs.

The construction hereinabove described with reference to Figures 1, 2 and 3 provides for supporting the bars 25 in positions parallel to the handle bar 19 but means may be provided for arranging the lines of type or matrices at right angles to the said handle bar. As shown in Figures 12, 13 and 14 rails 33 are suspended on hooks or clips 34 mounted on the ends of the rails 24 but it is obvious that the rails 33 may be mounted directly on the saddle bars 12. The rails 33 extend parallel to the handle bar 19 and support type or matrix supporting bars 35 by means of hooks 36, 37. The hook 36 is made to embrace more than two sides of the corresponding bar 35 and is made of a resilient material to allow the hook to be sprung onto the bar whilst the hook 37 is raised above the bar at the opposite side of the form. The hook 37 can then be pressed down on to this bar and secured in this position by a set screw 38.

The above arrangements are particularly applicable to forms and platens for use in presses of the type known as "cutter crush" presses, the above described constructions allowing the type or matrices to be used with the operative faces thereof opposite to the platen, the card or paper to be operated upon being placed on the platen beneath the type or matrices, or the type or matrices may be ar-

ranged with their operative faces uppermost, the card or paper then being placed thereon between these faces and the movable ram of the press.

Thus, if the rails 24 are inserted with the appropriate grooves 24a slid on to the saddle pieces 21, the operative faces of the type or matrices, when the saddle bars 12 are in their lowermost position, are out of contact with the platen, and when the saddle bars are raised by drawing out the slide bars 15 the type or matrices are carried further away from the platen to allow a card to be placed on the platen or removed therefrom. If it is desired to place the card above the type or matrices the latter are set up in the supporting bars with their operative faces uppermost and the rails 24 are put in such a position in the saddle pieces that the grooves which are then lowermost allow the rails to be lowered so that the backs of the type or matrices rest on the platen.

I claim:

1. A form comprising rails, type or matrix supporting bars separately adjustable along the said rails, means for securing the bars in different positions of adjustment along the rails, means provided on pairs of the said bars to support between them a type or matrix, and means separate from the rails for holding the bars in spaced relation.

2. A form comprising rails, type or matrix supporting bars separately adjustable along the said rails, means for securing the bars in different positions of adjustment along the rails, a type or matrix, interengaging ribs and slots on the type or matrix and the bars for supporting the type or matrix between two of the bars, and means separate from the rails for holding the bars in spaced relation.

3. A form comprising type or matrix supporting bars, a type or matrix, a distance piece, interengaging ribs and slots on the type or matrix and the bars for supporting the type or matrix between a pair of bars, clips on the distance piece for securing the distance piece to the bars, and extensions on the clips conforming to the shape of the bars.

4. A form comprising rails, bars separately adjustable along the rails, a distance piece, and spring clips on the distance piece to engage a pair of adjacent bars held in spaced relation by the distance piece.

5. A form comprising type or matrix carrying bars, bar supporting hooks, rails on which the hooks are adjustably mounted, said rails having grooves cut therein to different depths in different sides in the same transverse plane, and saddles having apertures to receive the rails, parts of the saddles sliding in the grooves in the rails which by inversion can be supported at different heights in the saddle determined by the depths of the slots.

6. A form comprising type or matrix carrying bars, a platen to which said bars are connected, type or matrices, interengaging ribs and slots on the type or matrices and the bars allowing limited movement of the individual type or matrices in the bars to different distances from the face of the platen and means engaging the bars to hold the same in spaced relation.

7. A form comprising type or matrix carrying bars, a platen whereon said bars are supported, type or matrices carried by the bars, interengaging ribs and slots on the type or matrices and the bars for supporting the type or matrices between pairs of adjacent bars and means engaging the bars to hold the same in spaced relation.

8. A form comprising type or matrix carrying bars, means engaging the bars to hold the same in spaced relation, bar supporting hooks, rails on which the hooks are mounted, saddles supporting the rails, saddle bars having the saddles mounted thereon, a platen, and means for supporting the saddle bars on the said platen.

9. A form comprising type or matrix carrying bars, means engaging the bars to hold the same in spaced relation, saddle bars having the said type or matrix bars attached thereto, a platen, slide bars, and pin and slot connections between the platen, the saddle bars and the slide bars whereby the type or matrix bars can be raised from or lowered towards the face of the platen.

10. A form comprising type or matrix carrying bars, clips engaging the bars, extensions on the clips conforming to the shape of the bars, bar supporting hooks, rails on which the hooks are adjustably mounted, saddles, hooks by which the rails are suspended from the saddles, saddle bars to which the saddles are attached, a platen and means for varying the position of the saddle bars to vary the distance between the type or matrix carrying bars and the surface of the platen.
